His ATTORNEY.

UNITED STATES PATENT OFFICE.

LEROY C. DOANE, OF MERIDEN, CONNECTICUT, ASSIGNOR, BY MESNE ASSIGNMENTS, TO THE MILLER COMPANY, OF MERIDEN, CONNECTICUT, A CORPORATION OF CONNECTICUT.

HOLDER FOR SHADES OR REFLECTORS.

Application filed October 4, 1922. Serial No. 592,417.

My invention relates to holders for shades and reflectors. The object of my invention is to provide an efficient holder which can be very conveniently mounted and operated to release or clamp the reflector or shade without injury thereto.

According to my invention, I provide an inner member which preferably comprises a plurality of prongs which are hook-shaped 10 at the bottom to engage the lip at the top of the shade or reflector and are sufficiently resilient to permit spreading to insert the lip of a reflector. A casing is provided having at its bottom a shoulder against which the 15 top surface of the reflector or shade bears. Means are provided for relatively moving the hooked prongs and the casing so as to clamp the lip of the shade or reflector between the hooks and the shoulder on the 20 outer casing. The casing serves, not only to provide the aforesaid shoulder, but also to confine the prongs, to prevent the spreading of the same, and to maintain their hooked 25 ends in firm engagement with the lip of the shade or reflector without exerting lateral pressure. The casing is preferably arranged so that it does not rotate during the clamping operation. In this manner, the clamping force may be exerted in an axial direction 30 only.

In the drawing I have shown one form of my invention. Fig. 1 is an elevation thereof; Fig. 2 is a vertical section; Fig. 3 is a top plan view; Fig. 4 is a plan view with the 35 casing cover removed; and Fig. 5 is a side elevation of one of the prongs.

Referring to the drawing, the usual porcelain socket 10 is provided for the reception of an incandescent lamp. The insulating upper portion 11 thereof is attached to a stud 12, the upper ends of prongs 13 being clamped between these parts. The stud may be used in fixedly supporting the lighting unit. This stud is threaded on the outside to cooperate 45 with the casing referred to. These prongs are preferably made of steel or other resilient material and have shade engaging hooks 14 at the free ends thereof. These prongs may be comparatively rigid as it is only necessary to spread them slightly to pass in the lip or bead of the reflector. The upper portion 15 of the reflector or shade is supported by the holder, the upper lip 16 thereof being engaged by the hooked prong ends 14, these 50 hooks being so shaped that they pass in

underneath the lip or bead, and to engage the lower surface thereof. A casing or cover is provided which preferably consists of two members 17 and 18. The former is provided with inner shoulders, or abutments 19, which are engaged by the upper surface 20 of the reflector or shade. The upper casing member or cap 18 has a heel extension 21 which is screw threaded internally to engage external threads on the stud 12. 60

In use, the cap 18 having been unscrewed, the lip of the reflector or shade is forced into engagement with the prong hooks. To facilitate placing the reflector in the shade engaging hooks 14, the inner wall of the casing 70 17 is flared outwardly at its lower end as indicated. The cap 18 is then screwed down upon the stud 12, forcing the lower member 17 downwardly toward the prongs 13, thus causing the clamping of the lip 16 between the hooks 14 and the shoulder 19. The casing member 17 bears against and keeps the hooks 14 in close engagement with the lip 16, while the prongs prevent rotation of the casing member about the socket. It prevents the spreading of the hooks without causing any wedging action which would tend to compress the reflector. The result is that the reflector or shade is held very securely and, at the same time, on account of the comparatively large bearing surface, the danger of breakage or injury is diminished. 80

To remove the reflector or shade from the holder, the member or cap 18 is unscrewed and the casing member may be raised so that the shoulders 19, are drawn away from the upper end of the reflector and the lower end of the casing member 17 having the larger diameter brought opposite the hooks which may now be spread to release the reflector. It will thus be noted that the pressure is applied in an axial direction only, without any tendency to squeeze or collapse the bead of the reflector. Also that on account of the extended surface, one is able to clamp the reflector in place by means of two prongs placed on opposite sides of the socket. To prevent the casing member from falling off the hooks 14, the lower ends of the hooks are made wider, as indicated in Figure 5 so as to engage the ends of the shoulders or abutments 19. 90

What I claim as new and desire to secure by Letters Patent of the United States is:

1. A holder for shades or reflectors com- 110

- prising members having hooked ends to engage underneath the lip of said shade or reflector, a casing extending about said members and having an inner shoulder engaging the top surface of said shade or reflector, and means whereby said hooked ends and said shoulder may be drawn together along the axis of the casing to clamp said lip or separated to release the same.
10. 2. In a shade holder, a casing having an interiorly disposed interrupted flange consisting of a plurality of spaced flange sections, a socket member mounted in said casing for axial movement relative thereto, hook arms carried by the socket member and engaging in the spaces between the flange sections, and means to move the socket member axially with relation to the casing whereby a shade lip engaged by the hook arms will be forced against the flange sections.
15. 3. In a shade holder, a casing having an interiorly disposed interrupted flange consisting of a plurality of spaced flange sections, a socket member mounted in said casing for axial movement relative thereto, hook arms carried by the socket member and engaging in the spaces between the flange sections, a screw threaded stud on the upper end of said socket member, and a cap threaded on the stud and engaging the upper end of the casing to move the socket axially of the casing upon rotation of said cap whereby a shade lip engaged by the hook arms will be forced against the flange sections.
20. 4. In a shade holder, a socket, a pair of members non-rotatably supported at the rear end of the socket and carried alongside the socket, the free ends of said members having shade engaging hooks, a threaded member carried by the socket, and a two part casing, one part being threaded to the threaded member, the other part being provided with interiorly disposed abutments positioned to engage the upper end of a shade, said hooks passing between the abutments to prevent relative rotation of the socket and said other part of the casing, the hooks engaging the lip of the shade and holding it in place as pressure is applied to the upper end of the shade by relatively turning the threaded parts to move the abutments axially of the socket toward the shade.
25. 5. In a shade holder, a socket, a pair of members non-rotatably supported at the rear end of the socket and carried alongside the socket, the free ends of said members having shade engaging hooks, a threaded member carried by the socket, and a two part casing, one part being threaded to the threaded member, the other part being provided with interiorly disposed abutments positioned to engage the upper end of a shade, said hooks engaging the lip of the shade and holding it in place as pressure is applied to the upper end of the shade by relatively turning the threaded parts to move the abutments axially of the socket toward the shade, the configuration of the casing being such that the hooks may be spread to release the shade only when the threaded parts are turned to permit moving the abutments away from the shade.
30. 6. In a shade holder, a socket, a pair of members non-rotatably supported at the rear end of the socket and carried alongside the socket, the free ends of said members having shade engaging hooks, a threaded member carried by the socket, and a two part casing, one part being threaded to the threaded member, the other part being provided with interiorly disposed abutments positioned to engage the upper end of a shade, said hooks engaging the lip of the shade and holding it in place as pressure is applied to the upper end of the shade by relatively turning the threaded parts to move the abutments axially of the socket toward the shade, said hooks having laterally extending shoulders engageable with the abutments to prevent removal of said other casing part over the hooks.
35. 7. A holder for shades or the like provided with a peripheral lip adjacent the upper end comprising, hook-shaped members relatively immovable in the direction of the axis of the shade and engageable underneath the lip, a movable casing having shoulders engageable with the upper end of the shade, and screw threaded means for forcing the shoulders in the direction of the axis of the shade toward the end of the shade lip.
40. 8. In a shade holder, in combination, a lamp socket, a pair of members fixedly carried by the socket structure, each member having a shade engaging hook, a casing carried outside the members and slidably therealong, said casing being provided with inwardly directed abutments between the members, screw threaded means for forcing the abutments in the direction of the axis of the shade toward the end of the shade, and cooperative screw threaded means for sliding the casing along the members and forcing the abutments against the upper end of the shade whose lip is engaged in the hooks.
45. 9. In a shade holder, in combination, a lamp socket, a casing outside the lamp socket, socket carried means cooperative with the casing for non-rotatably guiding it for reciprocation along the socket, screw threaded devices for effecting said movement, shade engaging means in the form of hooks fixedly carried by the socket and shoulders inside the casing, so arranged as to exert clamping force in an axial direction only.
50. 10. In a combined shade holder and lamp socket for use with a shade having a lip for engagement by the shade holder, a threaded stud at the upper end of the lamp socket, hook members attached to the stud and extending downwardly, a casing outside the hooked
55. 65. end of the shade by relatively turning the

members and having interiorly disposed peripheral flanges, the ends of which are spaced apart and between which the hook members pass to prevent relative rotation of the casing 5 and hook members, the hook members being engageable underneath the lip of the shade, and an upper cover member threaded on the stud and bearing on the casing to draw the hook members upwardly and cause the flanges 10 to press against the top of the shade for clamping the shade between the flanges and the hook members.

11. In a shade holder, in combination, a lamp socket, a casing outside the lamp socket, 15 straps fixedly connected at their upper ends to the socket and extending downwardly along the socket, casing carried means co-operative with the straps for non-rotatably

guiding the casing for reciprocation along the socket, the lower ends of the straps being shaped to engage underneath the lip of a shade, the lower end of the casing being provided with means to engage the upper end of the shade and with means to confine the lower ends of the straps to prevent radial 25 movement thereof when axial pressure is applied to clamp the shade in place, a screw threaded device also carried by the upper end of the socket, and a threaded member co-operative therewith and with the upper end 30 of the casing for axially moving the casing against the shade.

In witness whereof, I have hereunto set my hand this 29th day of September, 1922.

LEROY C. DOANE.
